UNITED STATES PATENT OFFICE.

KARL KLEINERT, OF STUTTGART, GERMANY, ASSIGNOR TO ROBERT BOSCH AKTIEN-
GESELLSCHAFT, OF STUTTGART, GERMANY.

ELECTRIC HEADLIGHT FOR VEHICLES.

Application filed October 14, 1921. Serial No. 507,702.

To all whom it may concern:

Be it known that I, KARL KLEINERT, a citizen of Germany, residing at Stuttgart, Germany, have invented certain new and useful Improvements in Electric Headlights for Vehicles, of which the following is a specification.

This invention relates to electric head lights for vehicles wherein each light carries a plurality of lamps, for example, a main lamp and one or more auxiliary lamps which are carried by the reflector and inserted from the rear into the latter. In the ordinary head lights of this type each lamp is fixed independently in the reflector, either by its holder being placed in a cover which is inserted from the rear into a corresponding slot in the reflector, or the socket is directly constructed in the reflector as is frequently the case where so called tubular lamps are employed. This arrangement has the disadvantage that in order to be able to remove the lamps from the reflector, the rear side of the latter must be made accessible. This is done by drawing the reflector out of the head light casing or swinging it back out of it. In doing this however the lamp sockets are separated from the current leads so that all the lamps of this head light go out and it is consequently quite dark. It is then of course difficult, or at least inconvenient, to remove the comparatively small lamps from the reflector and to insert them again particularly in the case of lamps whose sockets are constructed in one with the reflector.

In order to avoid this disadvantage, according to the present invention the sockets of all the lamps are arranged on a common carrier which is easily releasable and is attached to the reflector from the rear. With this arrangement in order to change the lamps it is only necessary to remove the one carrier from the reflector which can be done without trouble even in darkness, then the carrier with all the lamps can be brought into the light of the other head light and the changing of the lamps can be effected in a convenient manner. The arrangement according to this invention has the further advantage that the manufacture of a head light with a plurality of lamps is substantially simplified, on account of the construction of sockets in one with the sensitive reflector being avoided.

It is preferable to form in the reflector

separate openings, one for the insertion of each lamp, because the reflecting surface is thereby interrupted in a much lesser degree than where only one opening large enough for the insertion of all the lamps in the reflector is provided. By this arrangement, also, and particularly by the insertion and withdrawal of the lamps from the rear, the possibility of an accidental touching of the mirror surface, and hence the dulling of its polish, by the fingers in the act of inserting and withdrawing the lamps is practically obviated.

In order to make my invention more clear, I refer to the accompanying drawing, in which:

Fig. 1 is a vertical axial section of the entire head light.

Fig. 2 shows the crown part of the reflector, and

Fig. 3 a section of the lamp holder.

The reflector *a* is closed in front by a glass disc *b*; the reflector and the glass disc are held firmly in a covering ring *c* which, by means of a hinge *d*, is connected with the casing *e* of the head light. On opening the head light the reflector is therefore swung out of the casing *e*. The reflector *a* has two openings *f* and *g*, through which a main lamp *h* and an auxiliary lamp *i* project into the reflector. The sockets *k* and *m* for both lamps are mounted on a common support *o*. This has in addition a border or collar *p* which is inserted in a suitable support *q* on the reflector. The support *q* surrounds the opening for the main lamp *h* and is mounted on the rear side of the reflector. The two openings *f* and *g* in the reflector *a* are designed only of sufficient diameters to permit the insertions therethrough of the lamps *h* and *i*, respectively, and to provide for the location of the lamp sockets and holders in or adjacent the openings as shown in Fig. 1. With such openings, and the arrangement of parts permitting the insertion of the lamps therethrough from the rear of the reflector, the possibility of an accidental touching of the mirror surface of the reflector by the fingers in exchanging or adjusting the lamps in position is practically obviated. The holder *m* for the tubular lamp *i* is prolonged all round up to the reflector in order that the opening *g* at the rear may be entirely closed by metal. The lamp *i* has not however a separate guide in the reflector. Of course,

such a guide somewhat similar to that for the lamp *h* may be provided without departing from the scope of the invention. The lead connection terminals and the guide contacts for the two lamps *h* and *i* are mounted on a common insulating piece *r* which is connected with the casing *e* by a carrier *s* in any suitable way. The spring pressure of the contacts *t* and *u* prevent the lamp holder *o* from slipping out at the rear of the guide socket *q*. A further security such as a spring rest *v* or support on the socket *q* or the like may however also be provided.

If, for example, the main lamp *h* be burnt out and no other spare lamp is at hand, it is possible to employ the lamp *i* in place of the lamp *h*. For this purpose the reflector *a* is turned on the hinge *d* out of the headlight casing *e*. The rear of the reflector is then exposed, and the lamp holder *o*, together with the two lamps *h* and *i*, is withdrawn from the reflector by a single movement. After the lamp *i* has been changed for the lamp *h* the lamp holder with its collar *p* is again inserted in the support *q* whereupon the reflector is swung back into the casing *e*.

Having now described my invention, what I desire to secure by Letters Patent of the United States is:

1. An electric headlight for vehicles comprising, in combination, a reflector, a main lamp and an auxiliary lamp, a common holder for mounting both of said lamps within said reflector and with their current-receiving terminals exposed on said holder, current-supply terminals mounted adjacent the rear wall of said reflector, and means for detachably mounting said holder in the rear wall of said reflector with said lamp terminals in free contact with said current-supply terminals.

2. An electric headlight for vehicles comprising, in combination, a parabolic reflector, a main lamp and an auxiliary lamp, a

common holder for mounting both of said lamps within said reflector with their axes parallel with the major axis of said reflector, and means for detachably mounting said holder in the rear wall of said reflector, said means enabling a ready mounting of said holder in and a ready removal of said holder from said rear wall of said reflector.

3. An electric headlight for vehicles comprising, in combination, a parabolic reflector, a main lamp and an auxiliary lamp, a common holder for mounting both of said lamps within said reflector on spaced axes parallel with the major axis of said reflector and with the current-receiving terminals of said lamp exposed on said holder, current-supply terminals mounted adjacent the rear wall of said reflector, and means for detachably mounting said holder in the rear wall of said reflector with said lamp terminals in free contact with said current-supply terminals.

4. An electric headlight for vehicles comprising, in combination, a parabolic reflector, a main lamp and an auxiliary lamp, said reflector having separate openings in its rear wall, one for each of said lamps, of sizes just sufficient to permit the insertion of said lamps therethrough with their axes parallel with the major axis of said reflector, a common holder for said lamps enabling the aforesaid insertion of said lamp from the rear of said reflector and means for detachably securing said holder on a rear wall of said reflector to removably mount said lamps within said reflector in their said positions of insertion.

In testimony whereof I have affixed my signature in presence of two witnesses.

KARL KLEINERT.
